SIGNALING SYSTEM

Hallan Eugene Goldstine, Port Jefferson, N. Y.,
assignor to Radio Corporation of America, a
corporation of Delaware

Application March 7, 1945, Serial No. 581,412

6 Claims. (Cl. 332—28)

1

This application discloses a new and improved resonant line in a new and improved stabilizing circuit for a tube wave generator operating at very high frequencies.

The application also discloses the above stabilized generator in a wave frequency modulating system wherein the oscillation generator is coupled into the said improved line to generate stabilized oscillations and wherein the oscillations are modulated as to frequency by a modulator also coupled into the said line, and wherein the timing modulated oscillatory energy is supplied as excitation or output to a following tube or other load circuit by coupling the input of the same into the said improved line.

There is much need in the radio art for a simple relatively inexpensive wave generating and wave frequency modulating system that is reliable in operation, may be operated by a relatively inexperienced operator and will not get out of order while in service. For example, such a system is of wide use to our military forces for communicating relatively short distances between units and between control points and units, etc. A transmitter for such use must be of rugged construction and must be capable of operating at its assigned frequency over a considerable period of time under varying weather and temperature conditions without changing frequency.

In my improved system these requirements and others are met. Moreover, in my system the generated wave frequency does not change, even though the potential source may decrease considerably with use. The advantage of this is apparent. The frequency changing operations and apparatus are simple and reliable. The transmitter may be of relatively low power since the same is to be used over distances of the order of 40 miles. Although I have described my system as supplying the output to a working circuit, it will be understood that the same may be used as an excitation unit to supply amplifiers and/or frequency multipliers in turn feeding a load.

The ultimate object of my invention is improved transmitter circuits and operation.

Systems of this general type known heretofore, comprising generators of very high frequency wave energy and frequency modulators for the same, in many cases are too complicated for the need mentioned above. They usually include somewhat involved frequency stabilizing apparatus and circuits and usually make use of several tuning elements and controls for frequency changing purposes. These systems re-

2

quire trained operators and must be adjusted and regulated by experienced personnel.

The requirements to be met prevent use of A. F. C. apparatus and yet the system needs to be of substantially constant mean frequency, which is maintained under varying temperatures and varying power supply source potentials.

Since the mean frequency of the timing modulated wave energy is to be stabilized, some means for holding the frequency substantially constant is necessary, and a further object of my invention is an improved frequency stabilizing means. In my system this means takes the form of an improved resonant line. My improved resonant 15 stabilizing line, as included in the high frequency generating and modulating system in accordance with my invention, not only simplifies the whole arrangement, as will appear in detail hereinafter, but permits frequency changing adjustments to 20 be made with a minimum number of controls, and in fact permits operation and maintenance by a relatively inexperienced person.

A more specific object of my invention is a resonant line or similar high Q circuit wherein 25 the resonant frequency to which the line is adjusted remains substantially fixed, irrespective of changes in working temperature.

A further object of my invention is a simplified, structurally strong and readily adjustable resonant line wherein the resonant frequency remains substantially fixed irrespective of working temperature changes.

An additional somewhat specific object of my invention is an improved frequency stabilizing line 35 in an improved oscillation generating circuit with improved means for modulating the frequency of the oscillations generated, and improved means for supplying the generated frequency modulated oscillations to a circuit being excited such as, for example, an amplifier tube or a multiplier tube, or an antenna, directly or by way of an amplifier or multiplier tube.

In describing my invention in detail, reference will be made to the attached drawings, wherein 45 Fig. 1 illustrates by wiring diagram and schematically the essential features of a resonant line, an oscillation generator associated therewith to be controlled thereby, modulating means associated with the line and a load circuit excited by energy in the line.

Fig. 2 illustrates in detail by cross-section the essential features of a high Q resonant line arranged in accordance with my invention.

Fig. 3 illustrates a resonant line which is a modification of the line of Figs. 1 and 2.

In Fig. 1 of the drawings L5 is a high Q temperature compensated circuit in the form of a concentric line. This line described with reference to Fig. 2, as well as Fig. 1, comprises an outer member 10 and an inner member 12 having at the open end enlarged portions 12" and 12'', providing a lumped effect at this end so that the physical dimensions of the line may be less than the electrical dimensions thereof, which are about $\lambda/4$. With respect to the tank circuit formed by the line, this large diameter inner conductor may be considered the tank capacitance. The end plug portion 12''' is movable by means of screw 15 and may be considered a variable condenser in parallel with the main condenser formed by 12'', and provides the sole tuning means required in the tank circuit for tuning over the required frequency band. Resilient metallic fingers 136 make good contact between portions 12'' and 12''' of the inner conductor. At the other or closed end of the line the inner conductor is of smaller diameter and may be considered the tank inductance. Coupling loops L6, L7, L8, L9 and L10 are positioned in the resonant line in the space between the inner and outer conductors near the short circuited end. The large spacing between the inner and outer members 10 and 12 increases the surge impedance of the line at this end.

The electron discharge devices V1, V2 and V3 each comprise two electrode discharge systems in a single tube, but it will be understood that each of these tubes may be replaced by two tubes.

The tube V1 is the oscillation generator tube and has its electrodes coupled by the tank 10, 12, and loops L6 and L7 in an oscillation generator of the Meissner type. In this generator the control grids 16 and 18 are inductively coupled in pushpull relation to the tank circuit by loop L7. The anode electrodes 20 and 22 of the electron discharge systems in tube V1 are coupled differentially by the loop L8. It will be noted that the connections to the loop L7 are crossed to derive the opposed or 180° phase relation between the grid and anode voltages necessary in discharge systems operating as regenerative generators. The tube and loop couplings as described form a pushpull oscillator which is tuned by the resonant frequency control line L5.

Plate potential is supplied by a lead from a power supply source to a point on the center of the loop L6. The lead is bypassed for radio frequency by condenser 24. Bias for the control grids is supplied by connecting a point on the loop L7 through resistors R1 and R2 to ground. Unbypassed resistor R1 serves to damp parasitic oscillations, while grid leak resistance R2 shunted by bypass condenser 26 supplies grid bias for the oscillator.

Cathode bias for the tube V1 is supplied by resistor R13. The heater voltage supply lead terminals marked X-X', the plate voltage lead and the cathode return lead, to ground through resistor R13, of the tube V1, are each completed through radio frequency filters which keep the oscillator radio frequency voltage from causing undesired radiation and also keep radio frequency voltage out of the audio modulation, direct current supply and metering circuits. The bypass condensers on the heater, cathode and screen grid terminals of the socket for the tube used are built into the socket.

The tube V2 is similar in electrode arrangement to the tube V1 and may be of the same

tube controlled by signals for modulating the generated oscillations.

The anodes 30 and 32 of the electron discharge devices V2 are coupled in pushpull relation into the resonant circuit by coupling loop L8. The plate voltage is fed through the center tap of coupling loop L8 by line 38 running through the filter to the positive terminal of a direct current source. A condenser 40 is connected from this center tap to ground to bypass radio frequency voltages. The screen grids are also supplied with direct current from lead 36 through a potential dropping resistance shunted by a condenser 42 which bypasses audio to keep the same off the screen grids. The control grid coupling loop L9 has one end grounded, being thereby connected substantially directly to the cathodes of the discharge systems in V2. The other end of the loop L9 supplies radio frequency voltages from the resonant tank circuit L5 to the grid coupling condensers C5 and C6. These phase shifting condensers are of about like size, but one thereof is adjustable in order that the reactance tube sections may be balanced in case the capacitances and gains thereof are different. The two grids are fed in parallel by the radio frequency excitation voltage. The radio frequency voltage is impressed on each grid across the coils L1 and L3 which in combination with the resistors R4 and R5 respectively, and condensers C5 and C6 form phase shifting networks which shift the grid voltages 90° with respect to the voltage induced in loop L9. If the plates of the systems are excited by voltages 180° out of phase with respect to each other and the grids are fed by voltages displaced 90° , the phase of the voltage on the grid of one discharge system will lead the phase of the voltage on the plate of the same system 90° , and the phase of the voltage on the grid of the other discharge system will lag the phase of the voltage on the plate of the other system 90° . Thus the plate current in one electron discharge system will lead the plate voltage 90° , this system appearing as a capacitive reactance, and the plate current in the other system will lag the plate voltage thereof by 90° , this system appearing as an inductive reactance.

The reactance tube is connected so that when one half of the tube looks like a capacitive reactance, the other half appears as an inductive reactance. Then when the grids are modulated in pushpull as they are, when the capacitive reactance is decreasing the inductive reactance is increasing, both operating in a direction to lower the oscillator frequency. When the capacitive reactance is increasing in one tube, the inductive reactance of the other half of the tube is decreasing, both tending to raise the oscillator frequency. Thus potential variations applied to both sections of the tube simultaneously, such as screen grid voltage variations, hum, etc., do not cause the oscillator frequency to change, because these effects on the two sections balance and compensate. For details of this operation, reference is made to Crosby U. S. Patent #2,278,429, dated April 7, 1942.

The condensers C3 and C4 are radio frequency bypass condensers and coils L2 and L4 are radio frequency choking coils which prevent radio frequency from getting back into the audio lines 50. The audio frequency or modulating voltage is fed to the grids through coils L2 and L4 and applied to the grids through resistor coil combinations L1, R4 and L3, R5. The cathode return by lead 52 is first fed through a radio frequency filter which is near the tube socket and keeps the

radio frequency out of the tube leads and then through a second filter in the filter group at 48, and then through cathode bias resistance R12 to ground.

The generated and frequency modulated oscillations produced in the line L5 and tube V1 and frequency modulated by reactance tube V2 are supplied by loop L10, in the space between inner and outer conductors 10 and 12, coupled in push-pull fashion to the control grids 10 and 12 of a tube V3. In the embodiment tested, tube V3 operates as a frequency tripler. The tube V3 may be of the same type as the tubes V1 and V2. The advantages of using similar tubes throughout the system will be apparent. Tubes of only one type need be kept for replacement and interchange throughout the entire system. The center tap of the loop L10 is connected to ground by parasitic damping resistor R7 and grid leak resistor R8 shunted by a radio frequency bypass condenser C9. The cathodes of this tube are tied together and connected by a lead through a radio frequency filter in the group of filters and resistors R14 and R39 to ground. The screen grids of tubes 80 and 82 are supplied by positive direct current potential through resistor R9, lead 74 and one of the R. F. filters of the group of filters. The anodes of these tubes are also supplied direct current potential by lead 74. The cathode terminal is as in the prior tubes connected directly to ground by a condenser for filtering purposes. The resistors R14 and R39 supply the cathode bias for the tube.

The plate circuit of the systems in V3 is composed of rods L11 and variable dual condenser C43, the rotor plates of which are grounded. The other ends of the rods are connected to the anodes 80 and 82 of tube V3. The plate circuit may be tuned to the fundamental or a harmonic and in the embodiment used this circuit is tuned to the third harmonic of the frequency generated by the oscillator in tank L5. The radio frequency voltage between the rods varies along their length, being higher at the ends. The plate direct current voltage is fed through radio frequency chokes L14 at a place where the radio frequency voltage across the rods L11 is low. The junction point between the radio frequency coils L14 is connected directly to ground through a radio frequency bypassing condenser 83. Parasitic damping resistors R40 and R41 may be used across each of the inductances L14 to prevent undesired oscillations. The length of L11 is such as to provide a proper output impedance to the tube and to provide with condenser C43 tuning over the desired frequency range.

The output coupling loop L12 is positioned near the low frequency voltage point of the output circuit, this being a point where the current in the circuit is high and provides considerable magnetic coupling in the inductance L12. The loop L12 is fixed tuned by condenser C42. The radio frequency output from the line L11 is fed from the coupling coil L12 through a short length of coaxial transmission line or cable CL to radio frequency receptacle P1. The length of the line CL is not critical, as it is part of the transmission line to the antenna, and line CL should have the same surge impedance as the transmission line.

A diode V4 is coupled to the output coupling loop L12 by a line L13 to provide an indication of the radio frequency output voltage. This indication appears on meter MI when switch S1 is in the radio frequency position designated in the

drawings RF. One plate of the double diode V4 is connected through the short circuit end of the quarter wave length section of the radio frequency transmission line L13. This section of the line has an electrical length of about $\lambda/4$ and functions as an impedance transformer and permits a small amount of the output voltage to be impressed on the plate of diode V4, and thus prevents substantial loading of the output circuit by diode V4. The double diode V4 may be replaced by a single diode tube.

The heaters of the diode V4 are bypassed by condensers C11 and C12. The cathode 100 of diode V4 which is used is likewise bypassed to ground by condenser C13. This condenser shunts bias resistors R10 and R11 connected in series between the cathode and ground. The direct current metering voltage is taken across resistor R11 and is fed through a filter of the group of filters to switch S1, when in the radio frequency position RF, through meter MI, then through the resistor R16 to ground.

The meter MI by means of switch S1 is also arranged to indicate the cathode current of the modulation amplifier, not shown, when the switch S1 is on the contact labeled AMP. When the switch S1 is placed on the contact labeled V the volume of the modulator output, not shown, is indicated. The purpose of the contact RF has been described above. When the switch S1 is on the contact labeled AMP the cathode current to a modulation amplifier is measured. When the switch S1 is on the contact labeled MOD the current to the cathodes of the devices in the reactance tube V2 is measured. With the switch S1 on the contact labeled OSC the current to the cathodes of the oscillator tube V1 is measured, and when switch S1 is on the contact labeled PA the current to the cathodes of the power amplifier V3 is measured.

In my improved system, modulation of any type may be applied by connecting the modulator output to the leads 50. In the apparatus built, high quality audio channel and low quality audio channel is applied through an improved modulation amplifier system not claimed and described herein.

Details of the resonant line L5 are shown in Fig. 2. The line comprises the outer member 10 which may be mounted in any desired manner. In the embodiment built, the outer member 10 is flanged at each end and in the center and bolted at the open end to the rear wall of the transmitter housing, intermediate the ends to a center panel, and at the closed end to the inner front wall of the transmitter housing. The member 10 may be retained in position in any known manner. In the embodiment built, it is flanged as described and bolted to the transmitter wall panels and center panels. The inner line 12 is attached to the line closure member 109 which is in turn bolted to the front panel of the transmitter housing by the same bolts fastening line 10 thereto. The flange on which member 109 is bolted, is slightly tapered to provide contact on the inner perimeter of the flange. This provides low contact resistance and reduces variation in the position of the contact between the members. The members 10 and 12, in the embodiment constructed, are cylindrical. Member 12 extends along the axis of member 10 and is enlarged at 12''. The enlarged cup-like portion is welded or brazed or soldered to the reduced portion 12'. A second cup or plug portion 12''' partially within cup portion 12'' is joined to one end of a metallic

sleeve 115, the other end of which is fastened to a heavy washer or similar means 117 bolted to a sleeve 118. The sleeve 119 is thickened at 121 or attached to a heavier sleeve which is threaded on the inner periphery to cooperate with a square screw thread 132 on a shaft not numbered to move cup or plug member 12''' axially to protrude more or less from cup section 12'' for tuning purposes.

The shorted end of the outer member 10 has 10 a plurality of openings 110 therein into which the loops L6, L7, L8, L9 and L10 are inserted. In the particular embodiment described, the closed end of the line has five such openings 15 therein. The coupling loops are mounted on insulating material arranged in these openings. A loop so mounted is shown at 120. This loop might well be the loop L6 or L7 or L8 or L10 of Fig. 1. However, loop L7 is smaller than loops L6, L8 and L10. The insulating material 130 supports the 20 loop within the opening and also provides loop terminal and intermediate connectors 134.

The inner member 12 of the line has a reduced portion 12', a first enlarged cup shaped cylinder portion 12'', and a second enlarged cup shaped 25 plug portion 12''' which is adjustable. The plug-like adjustable portion 12''' is of larger diameter than the portion 12', but is smaller than the portion 12'' so that it may be moved in and out of the cylindrical portion 12'' to thereby vary the 30 total length of the line and tune the system, as described above. Beryllium copper, silver plated spring contacts 136 are arranged within the inner surface of the portion 12'' to make contact with the outer surface of 12''' as this movable plug portion is adjusted as to position by the screw member 15. The screw member 15 is on or attached to a shaft driven by knob or crank 140. The pinion 138 on the drive shaft drives a larger gear 142 carrying a dial or other indicating 35 means 144 arranged behind an opening in the front panel 141. The gear 142 has its point of rotation at 146 and the dial 144 is calibrated in frequency.

Returning now to the line, the member 12''', as stated above, is adjustable with respect to the member 12'' for tuning purposes. A spring 150 at one end bears against the flange member 117 supporting the plug member 12''', and at the other end bears against a member 154 which is fixedly mounted within the inner line portion 12' to force the inner line section 12''' in its most extended position against the thread screws 132. In other words, the spring 150 prevents an effect here similar to back lash in usual condenser drive arrangements. The screw 15 and its spindle sleeve 119 are made of Invar to hold the overall length of the line 12 substantially constant. The smaller cylindrical member or plug member 12''' is mounted on a sleeve 115 fastened to the flange 117. The cylindrical sleeve or guide member 115 slides on the outer surface of the inner line 12. The member 115 is made of brass, which has a higher coefficient of expansion than the metal of which the other portions 12' and 12'' of the inner conductor 12 is composed. Thus any expansion of the inner members 12' and 12'', excluding portion 12''', which takes place with changes in temperature is compensated by movement of the adjustable plug section 12''' in an opposite direction, due to expansion of the brass guide member 115, which takes place at a higher rate. The relative lengths of 115 and 12' and 12'' is such that substantially complete compensation for temperature changes is obtained.

In the embodiment built, the line 12, except for the portion 115, is made of cold rolled steel, the surface being silver plated for higher conductivity. The entire line could be made of Invar, if the same was at hand. When the member 12' and 12''' expands the member 115 expands in the opposite direction and thereby tends to compensate for difference in diameters between the large section 12''' and the adjustable plug section 12'''.

In the transmitter described, only two controls are used to tune the system to the desired frequency. To change the frequency of operation within the range covered by the system the main tuning knob 140 is turned until the desired reading is shown on the dial 144. This adjusts the length of the line L5 by adjusting the position of the inner cup member 12''' relative to the fixed parts of the line to thereby tune the line L5. Then the switch S1 is moved to close contact RF and the condenser C43 is tuned for maximum output, indicated in the meter MI.

Although it will be obvious that the tube arrangement, circuit element etc. depends in large part on the frequency at which it is operated, in the embodiment constructed the tubes V1, V2 and V3 are of the type RCA 829. The tube V4 is of the type RCA 6H6. The line L5 has a physical length of about 12 inches. The inner conductor has a physical length of about 9" at the high frequency end, and 11" at the low frequency end. The electrical length of a $\lambda/4$ length line at this frequency is about 36". The frequency of operation is in the 230 to 250 megacycle band. The oscillation generator V1 operated in the 76 to 84 meter band. V3 operated as an amplifier and frequency tripler. Modulation from 100 to 15,000 cycles per second may be applied. 100% modulation at 100 kc. deviation is obtainable at an output of 10-15 watts.

A modified means for providing temperature compensation is shown in Fig. 3. In this embodiment the line may be as shown in Fig. 1, except for the construction of the compensating cup 12''' of the line. The temperature compensation end 40 plug or cup 12''' is of alternate layers or sections of high and low expansion material, folded in such a manner as to increase the effective overall length of the correcting sleeve member 115. The square threaded spindle 15 is again of material 45 with a low coefficient of expansion, such as Invar, as is the sleeve 121, so that the distance between the line ends 109 and 117 is about constant with changes in temperature. The member 115 is of material such as brass, which has a high coefficient 50 of expansion. This sleeve 115 carries a folded back portion 115' made of material such as Invar, which does not materially expand with increases in temperature. This folded portion 55 carries a member 115'' made of a material which does expand with changes in temperature. For example, steel may be used here, or if more expansion is desired this member 115'' may be of brass. Now as the steel members 12' and 12''' expand to cause the cup 12''' to protrude further 60 from cup 12'' and lengthen the line, the sleeve 115 expands, as does the member 115'', to retract the cup 12''' to compensate the said expansion 65 and hold the total length of the inner conductor of the line constant.

If the steel parts of the frequency control line are made of steel having as low coefficient of expansion as obtainable, and the brass used for compensating has a relatively high coefficient of expansion, then the temperature coefficients of 70 the lines of both embodiments will be good.

What is claimed is:

1. In a signalling system, a resonant line comprising two parallel conductors conductively connected together at one end, said conductors having portions of close spacing and portions of wide spacing, apparatus for relatively adjusting the lengths of the conductors for tuning purposes, a tube generator having its input and output electrodes regeneratively coupled by loops in the space between said conductors, a reactance tube having its output electrodes coupled to a loop in the space between said conductors and having its input electrodes coupled to a loop in the space between said conductors, a phase shifting network in one of said last two couplings, an output tube having input electrodes coupled for excitation to a loop in the space between said conductors, and a load circuit coupled to said output tube.

2. In a signalling system, a resonant line comprising two parallel conductors conductively connected together at one end, said conductors having portions of close spacing and portions of wide spacing, a tube generator having its input and output electrodes regeneratively coupled by loops in the space between said conductors, a reactance tube having its output electrodes coupled to a loop in the space between said conductors and having its input electrodes coupled by phase shifting networks to a loop between said conductors, connections for applying modulating potentials to the input electrodes of said reactance tube, an output tube having input electrodes coupled for excitation to a loop in the space between said conductors, a load circuit coupled to said output tube, and means for varying the effective length of one of said conductors to tune said system.

3. In a signalling system, at least three electron discharge tube systems, a resonant line comprising two metallic telescoped cylindrical members electrically coupled at one end, the inner member comprising a portion of small diameter spaced by considerable distance from the other member, a portion of large diameter closely spaced to the other member and a second portion of large diameter physically adjustable in position relative to the other portion of large diameter for tuning the line, means for adjusting said second portion of large diameter relative to the other portion of large diameter, a regenerative coupling between one tube and said inner member for the production of oscillatory energy, a coupling between said inner member and the input and output electrodes of a second one of said tubes such that there is a phase quadrature relation between the generated voltages on said input and output electrodes, means for modulating the gain of said second tube, a coupling between said inner conductor and the input electrodes of the third tube, and an output circuit coupled to the output electrodes of the third tube.

4. In a modulation system, a resonant line comprising two metallic telescoped cylindrical members electrically coupled together at one end, the inner member comprising a portion of small diameter spaced by considerable distance from the other member, a portion of large diameter closely spaced to the other member and a second portion of large diameter physically adjustable in position relative to the other portion of large diameter for tuning the line, means for adjusting said second portion of large diameter relative to the other portion of large diameter, an electron dis-

charge device having input and output electrodes, means for coupling said device in a regenerative oscillation generator circuit including a first loop between said members coupled to the output electrodes of said device and a second loop between said members coupled to the input electrodes of said device, and means for modulating the frequency of the oscillations generated including a loop in the space between said members, a reactance coupled to the loop and means for varying the reactance in accordance with signals.

5. In a modulation system, a resonant line comprising two metallic telescoped cylindrical members electrically coupled together at one end, the inner member comprising a portion of small diameter spaced by considerable distance from the other member, a portion of large diameter closely spaced to the other member and a second portion of large diameter physically adjustable in position relative to the other portion of large diameter for tuning the line, means for adjusting said second portion of large diameter relative to the other portion of large diameter, an electron discharge device having input and output electrodes, means for coupling said device in a regenerative oscillation generator circuit including a first loop between said members coupled to the output electrodes of said device and a second loop between said members coupled to the input electrodes of said device, a reactance tube having input and output electrodes, a loop between said members coupled to said reactance tube output electrodes, a loop between said members coupled to said reactance tube input electrodes, a phase shifter in one of said last two couplings, and a source of modulating potentials coupled to said reactance tube.

6. In a signaling system, a resonant line comprising two parallel conductors conductively connected together at one end, means for relatively adjusting the lengths of said conductors to vary the tuning of the resonant circuit formed thereby, an electron discharge tube generator having input and output electrodes regeneratively coupled by loops positioned in the space between said conductors, a reactance tube modulator having input and output electrodes coupled to loops in the space between said conductors, a phase shifting network in the coupling between the input electrodes of said reactance tube and the loop in the space between said conductors, means for modulating the gain of said reactance tube in accordance with signals, and means for deriving output from said tube generator including an output circuit coupled to a loop in the space between said conductors.
